UNITED STATES PATENT OFFICE.

REUBEN W. AUBÉ, OF BROOKLYN, NEW YORK.

DESIGN FOR MOLDING FOR PICTURE-FRAMES, &c.

SPECIFICATION forming part of Design No. 23,903, dated December 25, 1894.

Application filed November 26, 1894. Serial No. 530,048. Term of patent 3½ years.

To all whom it may concern:

Be it known that I, REUBEN W. AUBÉ, a citizen of the United States, residing at Brooklyn, in the county of Kings and State of New York, 5 have invented and produced a new and original Design for Picture-Frame Moldings and the Like, of which the following is a specification, reference being had to the accompanying drawings, forming part thereof.

10 Figure 1, is a front view of a molding showing my design. Fig. 2, is a corner of the same. The chief features of my design consist in the ornamentation of flowers and leaves arranged as shown, and which is suitable for 15 picture frames and the like to be arranged substantially as shown in the accompanying drawings.

In Fig. 1, A are curved leaves which project out and up from the base of the molding. B, 20 are small flowers placed on the molding substantially as shown. C, are also small buds or partly open flowers which are placed on the surface of the molding, and between which are leaves or parts of leaves as at D.

At the corner of the frame is a bunch of 25 radiating leaves as shown at A. At B are flowers substantially the same as shown in Fig. 1.

The inner edge of the molding provided with the flowers, &c., terminates near the 30 corner with the arrangement of leaves D.

The leading feature of my design is the leafy and flowery ornamentation substantially as shown in the accompanying drawings all the parts being in relief.

At E, a suitable surface is shown for the 35 base of the molding, but other forms of surface may be used.

What I claim is—

The design for a molding for picture frames 40 and the like, substantially as herein shown and described.

REUBEN W. AUBÉ.
